UNITED STATES PATENT OFFICE.

FRANCIS W. JONES, OF NEW YORK, N. Y.

QUADRUPLEX TELEGRAPH.

SPECIFICATION forming part of Letters Patent No. 310,685, dated January 13, 1885.

Application filed June 26, 1884. (No model.)

To all whom it may concern:

Be it known that I, FRANCIS W. JONES, a citizen of the United States, and a resident of New York, in the county of New York and 5 State of New York, have invented certain new and useful Improvements in Multiplex Telegraphs, of which the following is a specification.

My invention relates to the transmitting apparatus of duplex and multiplex telegraphs, and is designed to prevent lagging and retardation of signals by providing an extra or clearing battery, which shall come into play at the 10 termination of a signal with a polarity the reverse of the signaling-current, so as to assist in the discharge of the line preparatory to a new signal.

My invention is designed more especially as an improvement on an invention described 20 in a prior application for patent filed by me April 5, 1884, No. 126,737. In that application I have described a transmitter system consisting of two transmitters and two sections of batteries normally charging the line, 25 and combined so that each transmitter when operated alone sends its signal by a current of the reverse polarity from that sent by the other, but with a tension less than that of the normal current, while both operated together 30 withdraw the signaling-battery or reduce the tension to such degree as to produce the practical effect at the receiving end of the line of no current.

My invention consists in the combination, 35 with such system, of a supplemental or clearing battery arranged to put to line a current of the opposite polarity to that of the normal charging-current, so as to assist in discharging the line at the time that said normal current or a reduced current of normal polarity 40 is withdrawn, as will be hereinafter more fully described.

My invention consists, further, in certain combinations of apparatus that will be more 45 specifically stated in the claims.

In the drawings I have illustrated diagrammatically the application of my invention to the system of transmitters and receivers shown in my prior application, before referred to.

50 A indicates the apparatus at the transmit-

ting-station, and B the apparatus at the receiving-station, of a line equipped according to my invention for sending two messages in the same direction.

By the employment of the well-known differential or Wheatstone bridge duplex it is obvious, for the purpose of sending messages in opposite directions without confusion, the capacity of the line may be doubled, as is well understood in the art. 55

I have for the sake of simplicity omitted the circuits and arrangements whereby this could be effected, as they are matters of common information with electricians. 60

T' T² indicate the two transmitters, each 65 operated, as usual in the art, by an electromagnet, which latter is to be controlled by a local battery and key, (not here shown,) while M' M² indicate, respectively, two sections of a main-line battery, controlled by said transmitters in such way that when both transmitters are at rest or in normal position both sections of battery may flow to line with a determinate polarity—say positive—while, if either of the transmitters be operated, a portion only of the battery will flow to line, the portion, and therefore, in the arrangement shown, the polarity, depending upon which key is actuated. If both keys are operated 70 together, both sections of the main battery are 75 withdrawn and no current flows to line.

The construction and the connections herein shown for producing this order of currents is as follows: Each transmitter is provided with a double contact-hook, a, and with two 85 contact-springs, b c, insulated from the transmitter-lever, but adapted by their resiliency to bear against and make contact with the hook when they are out of contact with the stops d f, respectively. When, however, the 90 lever is operated so as to bring either spring against its stop d or f, the spring is removed from contact with the hook, and at the same time makes connection with the stop. Each spring therefore, as is obvious, acts in conjunction with its stop and the hook after the manner of the ordinary continuity-preserving transmitter. The lever of the transmitter is so biased that normally the spring b shall be 95 in contact with the hooks, and the springs c in 100

contact with their stops, and the springs *b* and stops *d* may therefore be called the "front" contact springs and stops, and the springs *c* and stops *f* the "back" contact springs and stops.

5 The two terminals of the main battery $M' M^2$ are connected with the back stops *f*, and at an intermediate portion, near its center, said battery is connected with the front contact stops *d*. The springs *b* are connected to earth, 10 and therefore, as will be obvious, either key, when operated, will, through its front contact spring and stop, furnish a ground for the center of the battery, and will at the same time break the connection to line of that section of 15 the main battery connected directly with its back contact-stop, *f*. The other section of the main battery will find circuit to line through the back contact-stop and spring and stop of the key which is at rest, its earth connection 20 being furnished, as just mentioned, by the front contact and spring of the key operated.

In addition to the connections already described, the lever of transmitter T' is connected to the back contact-spring, *c*, of transmitter T' through the small battery $C B$, which is the clearing-battery, constituting the 25 main feature of my present invention, while the lever of the latter is connected with earth through an artificial resistance, R^3 , equal in amount to the resistance of the whole main battery $M' M^2$, plus that of battery $C B$ of the 30 whole main battery. Through this connection a circuit from line to earth is furnished independent of the battery when both transmitters are operated, such circuit being from 35 spring *c* of transmitter T' to hook and lever of the latter, thence to spring *c* of T' , hook and lever of the latter, and to earth. This connection is that provided for incoming signals 40 when the line is quadruplexed, and the artificial resistance R^3 interposed therein constitutes a provision whereby incoming currents may in the key system meet the same resistance when both keys are closed that they do 45 when both keys are at rest and the whole of the main-line battery $M' M^2$, plus the clearing-battery $C B$, is flowing to line. Artificial resistances $R' R^2$ are interposed between the contact-stops *d* and the battery for a similar 50 purpose, the resistance R' being equal to that of section M' of battery, that is withdrawn when transmitter T' is operated, and R^2 being equal to the resistance of section M^2 , plus that of the clearing-battery, both of which are 55 withdrawn when transmitter T' is operated.

The action of the apparatus and the order or system of currents, leaving out of consideration the presence of $C B$, which is made so small that no operation of the receiving-relays 60 is produced by it, is as follows: Normally, or when both keys are at rest, the circuit is from earth through front contact-spring, *b*, for T' , hook and lever of T , spring *c*, and stop *f* of T' , main battery $M' M^2$, stop *f*, and spring *c* of T' 65 to line, so that both sections of main battery flow to line with, say, a positive polarity. If

key or transmitter T' be operated, T' remaining at rest, the circuit for section M' is broken at stop *f* of T' , and the circuit is then from earth through *b* and *d* of $T' R'$, section M^2 of 70 battery-stop *f*, spring *c* of T' , lever and hook of T' to spring *c*, (which by the operation of the transmitter has been removed from contact with *f* and permitted to come into contact with the hook,) and to line. A current 75 of diminished strength and of the opposite polarity from section M^2 of battery is thus caused to flow to line. If transmitter T' alone be operated, T' remaining at rest, a current will flow to line from section M' of battery 80 with a positive polarity—that is, the same as when both keys are at rest—but with a diminished tension, the circuit being in such case from earth to spring *b* of T' , stop *d*, resistance R^2 , battery M' , stop *f* of T' , spring *c* of 85 the latter, and to line. If, while one transmitter is operated or depressed the other be operated, or if both be simultaneously operated, no current will flow to line, the connection of both poles of the main battery with 90 line being then broken at stop *f*, and the circuit being, as before described, from earth through resistance R^3 and the levers, hooks *a*, and springs *c*. The section of battery $C B$ may be of any desired number of cells, having 95 regard, however, to the proper play and order of currents to be sent by the transmitters by means of the signaling-battery $M' M^2$, and their proper action upon the receiving apparatus, to be presently described, or some 100 equivalent apparatus adapted to properly analyze the currents and control the reading-sounders. If battery M^2 be of twenty cells and battery M' of ten cells, clearing-battery $C B$ might be of five cells. Battery $C B$ is, it 105 will be observed, placed in the connecting-wire with its negative pole connected to the lever and hook of transmitter T' , so that whenever the latter is operated said battery will flow to line with a current the reverse of the 110 normal signaling or charging current from signaling-batteries $M' M^2$. If both transmitters be operated together and both signaling-batteries be withdrawn, battery $C B$ is put to line with a reverse polarity, and helps 115 to discharge the line, as is well understood in the art. Similarly, if transmitter T' alone be closed, battery $C B$ flows and assists section M^2 , which then flows with a negative polarity, and if the previous condition of line be one 120 in which a positive current flows, as is the case when both keys are closed or B alone closed, assists in discharging the line. These conditions and effects will be readily seen to exist if the operations before described be followed, with the understanding that the clearing-battery $C B$ is in the connection shown. 125

At the receiving-station $D' D^2$ indicate two polarized relays of any ordinary or desirable kind, and D^3 a third relay, which may be either 130 a polarized or a neutral relay, but is here indicated as polarized. Its office is to close con-

tacts in the local circuit when the normal current on the line is reduced by the operation of a transmitter.

S' S² indicate reading-sounders in normally-open local circuits controlled by the relays. The sounder S' is controlled by relay D', and responds to signals sent by transmitter T'. Sounder S² is in a local circuit in which are two breaks—one at the contact-stop of relay D² and the other at the contact-stop of relay D³—the circuit for said sounder being completed through the relay-levers and their contact-stops in series. This sounder responds to signals sent by transmitter T², and can obviously only respond when both relay-levers are against their contact-stops. Relay D' is polarized so that a positive current, whether of a maximum or of a diminished tension, will hold its contacts open. A negative current will cause its lever to move, assisted by the retractor r', and close the local. Also, if no current or a very weak current flow to line, the bias given to the relay-lever by spring r' will cause the sounder-circuit to be closed. Relay D² is polarized so that a positive current of any strength will close its contacts. A spring, r², assists in this action, and also gives the lever a bias which causes the contacts to be closed if no current or a very weak current flow to line. A negative current—that is, one of the polarity which will close the local of S'—will cause the opening of the contacts of relay D², the spring r² being of insufficient tension to hold the lever in the position shown. Relay D³ is polarized, so as to hold its contacts open by the action of a positive current of a sufficient tension to overcome its retractor r³. The latter is set above the tension of the retractors of the other relays, and a current of the maximum tension, or that which flows when both transmitters are at rest, is required in order to overcome the spring and keep the local of S² open at this point. If a diminished current be sent by the closing of either key singly, or if both keys be closed together, so as to cut off the flow of current, the retractor r³ will close the local of S² at such point, and if the contacts of relay D² be also closed at such time, the sounder will respond. If the diminished current be a negative current, or one by which S' alone should respond, the relay D' will open its contacts before the spring r' can cause the closing of the contacts of D³, and S² will, therefore, remain unaffected, as it should do; but if the diminished current be a positive current—that is, of a polarity to hold contacts of D² closed—the circuit of S² will obviously be completed by the movements of the lever of D³ against its contact-stop, and S² will respond. It will likewise respond if no current flow to line, because, obviously, in this case the contacts of D² are closed by the spring r².

The operation is as follows: When both transmitters are at rest, a maximum current or from both sections of battery flows with

positive polarity. The contacts of relay D' remain open, as do those of relay D³, the current being of sufficient strength to overcome the retractor r³. The contacts of D² are closed by the action of this current; but the circuit of S² is open at D³. If transmitter T² be operated, a current from section M' of battery only flows to line with a positive polarity. This current is insufficient to overcome the retractor r³, and the sounder S² operates. Sounder S' remains unaffected, because the retractor r' is set below the effects of a diminished current of positive polarity. If while T' is at rest T² be operated, a current of diminished strength, but of negative polarity, flows to line and relay D' closes its local and sounder S' responds. Relay D² opens its contacts and keeps the local of S² open, although relay D³, by the action of such reversed current and the retractor r³, closes its contacts. Under this condition the signaling-current is from section M² of battery, but is combined with the current from the clearing-battery, which is, however, so small that the tension of M' and C B is less than that of the normal or charging current, and the effect of C B is to assist in bringing about a reversal of the line condition if the previous condition be one of positive current. If, now, while T² is closed T' be also closed, the whole battery is withdrawn from line, and the retractor r³ of relay D² closes the local of S², the relay-contacts now being all closed by the action of the retractors. The same action obviously takes place if both transmitters are operated simultaneously so as to cut down the maximum current of a positive polarity to zero. In such case the retractors r' and r³ act and close the locals. The operation under the latter suppositions is accompanied by the placing of the clearing-battery to line, which not only assists in clearing the line but in producing the closure of the local for S' if at the time of the operation the line-current be a positive one. The tension of the battery C B is insufficient to cause the armature of relay D² to overcome its retractor, and it does not therefore interfere with the action of the latter relay under the condition produced by the closure of both transmitters T' T².

What I claim as my invention is—

1. The combination, with two sections of main battery, a normally-charged circuit, and two transmitters, which respectively send signals by currents of diminished tension, but of opposite polarity, and when operated together cut off both sections of main battery, of a supplemental battery for clearing the line, said battery being placed in the circuit when both transmitters are closed, and having its poles connected in circuit, so as to place to line a weakened current of opposite polarity to that flowing when both sections of battery are to line.

2. The combination, substantially as described, in a multiplex telegraph, of a nor-

normally-charged circuit, two transmitters which send each a current of opposite polarity to that sent by the other, but of a tension less than that of the normal current flowing when both are at rest, and when operated together send a signal by withdrawing the main or signaling battery, and a supplemental or clearing battery connected to line, with a polarity the opposite of that for the main battery when both sections of the latter are to line.

3. The combination, with two transmitters that individually send each a current of the opposite polarity to that sent by the other, but of a tension less than that of the normally-flowing current, and when they are operated together reduce the current, of a supplemental or clearing battery in the circuit when both keys are closed, but with a polarity the opposite of the normally-charging current.

4. The combination, with the two double-hook transmitters, the two sections of main battery connected at an intermediate portion to

normally-open ground-point of the two transmitters, and at its extremities, respectively, to the normally-closed line-connecting points, of 25 a supplemental or clearing battery in a connection between the two transmitters, and having a reverse pole to that of the main charging-battery connected to line when both transmitters are operated.

30 5. The combination, substantially as described, of the two sections of main battery, the clearing-battery C B, and artificial resistances R' R², one equivalent to the resistance of one section of main battery, and the other 35 equivalent to the other section of battery plus that of clearing-battery C B.

Signed at New York, in the county of New York and State of New York, this 21st day of June, A. D. 1884.

FRANCIS W. JONES.
